Filed June 13, 1966, Ser. No. 2,663

Term of patent 14 years

(Cl. D23—97)

The broken line showings in FIGURE 1 of a support stand and a flue are merely for illustrative purposes.

I claim:

The ornamental design for a free standing fireplace, substantially as shown and described.
